UNITED STATES PATENT OFFICE.

HENRY D. POWNALL, OF CANTON, OHIO.

ICE-MACHINE.

1,180,530.

Specification of Letters Patent. Patented Apr. 25, 1916.

Application filed February 7, 1913. Serial No. 746,825.

To all whom it may concern:

Be it known that I, HENRY D. POWNALL, a citizen of the United States, residing at Canton, in the county of Stark and State of Ohio, have invented certain new and useful 5 Improvements in Ice-Machines, of which the following is a specification.

My invention relates to improvements in ice machines, and particularly to certain 10 features of my invention as originally set forth and claimed in my application Serial No. 597,746, filed December 17, 1910. One of its objects is to provide an improved construction and arrangement of the brine tank 15 and ice molds adapted to the production of ice from raw water.

Another object is to provide for the convenient detachment and removal of defective ice molds and the replacing of new 20 ones, and to provide for cutting one or more of the ice molds out of active service.

Another object is to provide improved means to seal the ice molds in place to avoid leakage from the tank or leakage between 25 the brine and fresh water compartments.

My invention also comprises certain details of form, combination and arrangement, 30 all of which will be fully set forth in the description of the accompanying drawings, in which:

Figure 1 is a plan view of a plurality of brine tank units with their contained ice 35 molds and with the lids removed. Fig. 2 is an enlarged vertical section on line *v-v* of Fig. 1. Fig. 3 is a perspective view partly in section of one of the ice molds detached. Fig. 4 is a similar view illustrating a modification.

The accompanying drawings represent 40 the preferred embodiment of my invention in which—

I represent separate brine tank units to contain a non-congealing cooling medium which may be cooled directly in said tanks, 45 but is preferably circulated to and from said brine tanks from a brine cooler. The bottoms of the brine tanks are provided with a series of openings 2 over which the ice molds B are detachably seated in order to 50 provide for pipe connections through the bottoms of the brine tanks to the bottoms of said ice molds, and to provide for readily removing the ice molds when they become injured or defective to conveniently replace 55 them with new ones to save time and avoid discarding the entire tank unit. The ice

molds preferably comprise rectangular sheet metal containers vertically arranged within the brine tanks so as to leave space 3 of practically uniform width between the adjacent 60 walls of said molds and between said molds and the tank walls to receive the brine, and insure a uniform brine circulation and rate of freezing in the ice molds.

The bottoms 4 of the ice molds are preferably set up some distance above the bottoms of the brine tanks, and the lower edges of the side walls of the ice molds extend down to and preferably rest upon gaskets N on the bottom of the brine tanks. The 70 lower edges of the ice molds are preferably either turned inwardly to form a ledge b by means of which the ice molds may be clamped to the tank bottoms as illustrated in Fig. 4, or as illustrated in Figs. 2 and 3, angle irons 5 are attached all around to the lower edge of the side walls of the ice molds, which angle irons project inwardly from said side walls and enable the ice molds to be clamped firmly but detachably, 75 to the brine tank bottoms by means of bolts 6 and nuts 7, said bolts and nuts being preferably of brass, or silverized, to prevent corrosion, and to enable the bolts and nuts to be readily detached. The gaskets N may 80 be of roofing felt, rubber or like substance. Access to said bolts is had through the openings 2 in the bottoms of the brine tanks.

The lower portion of the space in the brine tank surrounding the ice molds is 90 filled in with pitch or a similar material E in a heated or semifluid condition up to the level of the bottoms 4 of the ice molds, said pitch becoming practically solid on 95 cooling and serving to seal all the joints at the bottom of the molds and tanks to prevent leakage in any direction, and also to provide a non-conducting or insulating material to moderate the temperature at the bottoms of the ice molds and in the chambers 9 beneath the ice molds to prevent the fresh water freezing in the conduits leading through the openings in the bottoms of the brine tank to the bottoms of the ice molds.

In practice the brine tanks are seated in 100 an elevated position above the floor 10 as for instance upon piers 11 and T-bars 12, so as to afford access to the bottom of the brine tanks. Fresh or raw water is supplied to all of the ice molds of a given brine tank, 110 at one time through coupling members f and branch pipes 14 leading from a main

- valve controlled supply pipe 15 and freezing in all the ice molds of one brine tank is commenced at one time by circulating cold brine through said tank. A series of branch pipes 16 connected to a valve controlled main 17 enables a limited proportion of the raw water charged with impurities to flow from the ice molds through the main 17 to a settling reservoir where the impurities settle out, and the raw water returned by way of pipes 14 and 15 to the ice molds. A limited quantity of air under pressure is supplied to the respective ice molds through branch pipes 18 and mains not shown, and allowed to bubble up through the raw water in the ice molds and to escape at the top of the ice molds, this air serves to agitate the water in the ice molds to free the face of the forming ice from air bubbles, salts, sediment, or other impurities, separated out during the freezing process, to produce clear and pure ice, and also to promote a circulation of raw water to and from the ice molds through the settling reservoir 19. When the ice molds are nearly filled with ice all the water remaining therein is drained off through a waste cock 20 to remove all impurities from the ice molds, and the space refilled with clear water and the air circulation stopped and the brine circulation continued until all the water in the ice molds except a small fraction directly over the conduits at the bottom of the ice mold has become solid, whereupon the circulation of cold brine is discontinued and the cold brine in the brine tank is replaced with warm brine which serves to loosen the ice from the walls of the ice molds to permit it to be removed, whereupon all the ice from one brine tank is removed and the molds again filled with raw water ready to repeat the freezing operation.
- Should any of the ice molds become injured or defective during the warm or active season, I preferably disconnect all the branch conduits leading thereto and cap the same leaving said defective ice mold in dormant state until the cold or dormant season when it can be conveniently and readily replaced with a new one. In order to replace a defective ice mold the water is withdrawn from the defective mold and the brine drained from the tank in which it is seated. Then the bolts 6 and nuts 7 of said defective mold are removed and the walls at the lower part of the ice mold are heated by means of a blow torch or similar means which loosens the ice mold from the pitch E and permits the mold to be withdrawn vertically and a new ice mold substituted, which is bolted in place upon the tank bottom and then its lower side walls heated whereupon the pitch adheres thereto forming a sealing joint. By providing inwardly projecting means to clamp the ice molds to the bottoms of the
- brine tanks the ice molds may be detached and replaced without to any extent disturbing the pitch or sealing material. If desired valves may be employed in the branch conduits to enable defective ice molds to be cut out of circuit until such time as it may be convenient to replace them, but due to the cost of a multiplicity of valves and the liability of leakage therethrough, I prefer to detach and cap the branch conduits of defective molds until such time as they can be conveniently replaced.
- The apparatus herein illustrated and described is capable of considerable modification without departing from the principle of my invention.
- Having described my invention what I claim is:
1. An apparatus for making artificial ice comprising a refrigerating tank having an opening in the bottom thereof, a container for the water to be frozen, having its bottom exposed to the atmosphere through said opening in the tank bottom, said container having a marginal flange at the bottom thereof extending around said opening, means to detachably hold said flange in contact with the tank bottom, a sealing medium forming a water tight joint between said container and tank bottom and means to circulate a refrigerant through said tank.
  2. An apparatus for producing artificial ice, comprising a brine tank having an opening in the bottom thereof, a container for the water to be frozen detachably fitted over said opening in the tank bottom, said container having an inwardly turned flange below its bottom to engage and seat upon the tank bottom around said opening, and means to clamp said inwardly turned flange to said tank bottom.
  3. An apparatus for producing artificial ice, comprising a brine tank having an opening in the bottom thereof, a container for the water to be frozen detachably fitted over said opening in the tank bottom, said container having an inwardly turned flange below its bottom to engage and seat upon the tank bottom, and bolts passing through said flange and tank bottom to clamp said container in place.
  4. An apparatus for producing artificial ice, comprising a refrigerating tank having an opening in the bottom thereof, a container for the water to be frozen detachably fitted over said opening in the tank bottom, said container having an inwardly turned flange at its bottom to engage and seat upon the tank bottom, means around the bottom of the container to prevent leakage thereunder, and means to detachably clamp the container down upon the bottom of the refrigerating tank.
  5. An apparatus for producing artificial ice, comprising a refrigerating tank having

an opening in the bottom thereof, a container for the water to be frozen detachably fitted over said opening in the tank bottom, said container having an inwardly turned flange at its bottom to engage and seat upon the tank bottom, a strata of sealing material capable of being rendered plastic by the application of heat surrounding the bottom of said container to prevent leakage thereunder, and means to detachably clamp said container down upon the bottom of the refrigerating tank.

6. An artificial ice producing apparatus comprising a tank having an opening in its bottom, an ice mold seated over said opening and detachably secured to the bottom of said tank, and a coupling member attached on the outside to the bottom of said ice mold to conduct water and air to said ice mold through the bottom of said tank.

7. An artificial ice producing apparatus comprising a brine tank, an ice mold having inwardly turned flanges seating against the bottom of the tank, means to detachably

secure the ice mold to the tank, a coupling member connected on the outside to the bottom of the ice mold to introduce water and air to said ice mold, and a body of sealing medium occupying the lower portion of the tank and surrounding the lower portion of the ice mold to seal the joints at the bottom of said tank and ice mold.

8. An artificial ice producing apparatus comprising a brine tank, a metal frame mounted above the floor and supporting said tank in an elevated position above the floor, an ice mold located in and detachably connected to the bottom of said tank, a coupling member attached on the outside to the bottom of said ice mold, and means to supply water and air to said ice mold through said coupling member.

In testimony whereof I have affixed my signature in the presence of two witnesses.
